UNITED STATES PATENT OFFICE

170,798

TOOLHOLDER

Burton W. Dundon and Leo O. Dundon,
Kalamazoo, Mich.

Application August 18, 1952, Serial No. 21,080

Term of patent 14 years

(Cl. D58—13)

To all whom it may concern:

Be it known that we, Burton W. Dundon and Leo O. Dundon, citizens of the United States of America, residing at Kalamazoo, Michigan, have invented a new, original, and ornamental Design for a Toolholder, of which the following is a specification, reference being had to the accompanying drawing, forming a part hereof, wherein

Figure 1 is a perspective view of a toolholder, showing our new design.

Figure 2 is a cross-sectional view thereof, taken on the line 2—2 of Figure 1; and

Figure 3 is a cross-sectional view thereof, taken on the line 3—3 of Figure 1.

The rear view and side view not shown are the same as those shown.

We claim:

The ornamental design for a toolholder, as shown and described.

BURTON W. DUNDON.
LEO O. DUNDON.
